UNITED STATES PATENT OFFICE.

NUNEZ CLARENCE FERRIS, OF NEW YORK, N. Y.

MUSIC-SHEET-TRACKING DEVICE.

1,365,312.

Specification of Letters Patent. Patented Jan. 11, 1921.

Application filed May 3, 1920. Serial No. 378,549.

To all whom it may concern:

Be it known that I, NUNEZ CLARENCE FERRIS, a citizen of the United States, residing in the city of New York, borough of Brooklyn, in the county of Kings and State of New York, have invented a certain new and useful Improvement in Music-Sheet-Tracking Devices, of which the following is a specification.

- 10 The invention relates to devices for automatically maintaining the perforations in the moving music-sheet in alinement with the music-ports of the tracker-bar in self-playing musical instruments, and the object of the invention is to provide simple, and 15 eminently efficient means for automatically accomplishing the desired result by shifting the tracker-bar as required in following the lines of perforations in the sheet.
- 20 Another important object is to provide means for shifting the tracker-bar in transposing or raising or lowering the pitch or key as desired, and for maintaining the alinement in the changed position of the bar.
- 25 The invention consists in certain novel features of construction and arrangement by which the above and other objects are attained, to be hereinafter described and claimed.
- 30 The accompanying drawings form a part of this specification and show the invention as it has been carried out in practice.

Figure 1 is a front elevation showing the tracker-box and adjacent portions of the mechanism, sufficiently to permit the invention to be understood.

Fig. 2 is a corresponding plan view, partly in horizontal section.

Fig. 3 is a rear elevation of the tracker-bar, on a larger scale.

Figs. 4, 5 and 6 are vertical sections taken respectively on the lines 4—4, 5—5 and 6—6 in Fig. 3.

Fig. 7 is a horizontal section through the 45 pneumatic controlling the shifting movements of the tracker-bar.

Fig. 8 is a transverse vertical section of the same, taken on the line 8—8 in Fig. 7, and partly in elevation.

50 Fig. 9 is an elevation of a portion of the tracker-bar.

Similar letters of reference indicate the same parts in all the figures.

A A are the side walls of the tracker-box, 55 B is the music-roll, B¹ the winding spool, and B² the gearing, only partially represent-

ed, for driving the roll and spool, all of the usual or any approved construction.

C is the tracker-bar suspended by a link C¹ at each end, pivotally connected to the walls A A or other relatively fixed support, and free to swing longitudinally in both directions. Its rear face rides on antifriction rollers A¹ A¹ mounted in the side-walls A, see Fig. 2, and it is held in contact with the rollers by gravity and the tension of the music-sheet M. The tracker-bar is provided with the usual music ports c having nipples c¹ connected by tubes, not shown, to the player pneumatics as usual.

At one end of the tracker-bar is a longitudinal dovetailed recess or undercut groove c² in which is mounted a slide D matching to the groove and to the outer face of the bar, and movable longitudinally thereof. The slide has a port d and a connecting nipple d¹ therefrom extending through the slot c³ in the bar, leading from the groove c².

E is a thin narrow rod or strip, preferably of steel, lying in a shallow groove c⁴ in the rear face of the tracker-bar and confined therein by fixed bridges C². The rod projects longitudinally beyond one end of the tracker-bar and forms the connection by which the tracker-bar is swung or shifted as required in maintaining alinement of the music-port c with the music perforations in the music-sheet.

The rod E is positively but adjustably connected to the slide D by a nut E¹, mounted on a screw E² fixed on the rod, and protruding through a close-fitting slot d² in the slide, so that it may be turned from the front. The movement of the tracker-bar is automatically effected through the rod E by means of a peculiarly constructed pneumatic 95 mounted adjacent the tracker-box.

This pneumatic comprises a horizontally disposed base F having two cavities F¹ F² located side by side therein, each covered by a flexible diaphragm, marked F³ F⁴ respectively. The diaphragm F⁴ is of considerably greater area than the diaphragm F³; the latter carries a vertical stud F⁵ and the diaphragm F⁴ carries a similar stud F⁶. The 100 studs are connected to opposite arms of a light beam G fixed on a transverse shaft G¹ mounted in bearings F⁷ on the base F between the diaphragms, and having a vertical arm G² pivotally connected to the projecting end of the rod E.

Thus arranged, a tilting movement of the

beam G causes the arm G² to swing in a vertical arc and induces a corresponding longitudinal movement of the tracker-bar C relatively to the music-sheet M, and if 5 such movements be properly initiated and controlled, the desired alinement of ports and perforations will be maintained.

Leading from the cavity F¹ is a nipple f¹ connected to a suction pipe f³ by which 10 a partial vacuum is produced beneath the diaphragm F³, and leading from the cavity F², beneath the diaphragm F⁴, is a nipple f² connecting through a flexible tube f⁴ with the nipple d¹ and port d in the slide D. 15 The port d is located by adjustment to lie partially covered by the margin of the music-sheet M, with the port nearly closed under normal conditions of proper alinement. A constricted bleed-opening h in 20 the wall of the cavity F² connects through a bleed passage h¹ with the cavity F¹ and is controlled by a needle valve H, allowing the partial vacuum in the cavity F¹ to draw continually from the cavity F² a limited 25 amount of air, entering at the partly closed port d, just sufficient to hold both diaphragms balanced and the arm G² practically stationary.

When the music-sheet travels to the 30 right, in Fig. 1, in the direction to cover the port d, the admission of air is lessened or stopped and a partial vacuum forms in the cavity F² by the exhaust through the bleed, and although the pressures may be 35 equal in both cavities the area of the diaphragm F⁴ being greater than that of the diaphragm F³ permits the pressure of the atmosphere to force down the diaphragm F⁴ against any opposition by the dia- 40 phragm F³, tilt the beam G and through the arm G² and rod E, swing the tracker-bar to the right to open or expose the port d, and by such movement again bring the music-ports c into alinement with the music 45 perforations.

When the music-sheet M wanders to the left, in Fig. 1, and admits air too freely through the port d, as by completely uncovering the latter, atmospheric pressure in the 50 cavity F² equals the external atmospheric pressure and the diaphragm F⁴ is neutralized; thus conditioned air pressure on the smaller diaphragm F³ becomes effective and by forcing down this diaphragm tilts the 55 beam G in the opposite direction and through its connections shifts the tracker-bar to the left until the port d is again partially closed. The preferred normal condition is illustrated by the dotted line in 60 Fig. 9 which indicates the margin of the sheet M relatively to the port.

It will be noted that the alinement is maintained and the shifting movement of the tracker-bar induced in both directions 65 by the position of the sheet-margin rela-

tively to a single port d, and by adjusting the slide D, through the medium of the nut E¹ and screw E², the port may be located very exactly in position to insure perfect alinement.

Transposition to a higher or lower key 70 forms an important part of the invention and the alinement mechanism above described permits its easy accomplishment. On the rear face of the rod E is secured 75 a short rack J in the teeth of which meshes a small pinion J¹ located above the rack and operated by a head J² on the front of the tracker-bar. The lower face of the rack is notched transversely and a spring dog K 80 mounted on the tracker-bar is arranged to engage either of the notches presented there- 85 to. The notches are spaced to correspond to the spaces between adjacent ports c, so that by partially rotating the pinion J¹ the en- 90 tire tracker-bar may be moved to the right or left (Figs. 1 and 2) relatively to the rod E and correspondingly lower or raise the key in which the music will be played.

Four notches j¹, j, j² and j³ are shown, 90 see Fig. 3, which it will be noted is reversed relatively to Figs. 1 and 2. When the dog K is engaged in the notch j the key will be normal; with the dog engaged in the notch j², as in Fig. 3, the key is lowered one half 95 tone; engagement in the notch j³ lowers the key another half tone or one whole note below normal, and when engaged in the notch j¹ the key will be raised one half tone above 100 normal. The number of notches and cor- 105 responding changes in key may be varied as found desirable.

If the notches are exactly spaced the 110 transposition in nowise affects the alinement action, for the reason that the slide D with its port d is correspondingly moved; if however the shift for transposition 115 throws the music ports c out of alinement with the music perforations, the port d may be readily adjusted by the nut E¹ to make 120 any necessary correction relatively to the margin of the music-sheet.

Modifications may be made in the forms and proportions without departing from the 115 invention in adapting it to various types of 125 self-playing instruments.

The tracker-bar may be supported by other means than the suspension links C¹; the latter are preferred as offering freedom of movement with a minimum of friction, 120 and the transposition device may be employed with other forms of alinement devices.

I claim:—

1. In a device of the character set forth, 125 a traveling music-sheet having music perforations, a freely suspended swinging tracker-bar movable in both directions transversely of said sheet and having music ports and a single alinement port, and means ac- 130

tuated by the position of said sheet relatively to such alinement port, for moving said tracker-bar in either direction and maintaining alinement of its music ports with such 5 perforations.

2. In a device of the character set forth, a traveling music-sheet having music perforations, a freely suspended swinging tracker-bar movable in both directions transversely of said sheet and having music ports and a single alinement port, and means actuated by the lateral deviations of said sheet to expose or cover a greater portion of such alinement port, for moving said tracker-bar 10 in either direction and maintaining alinement of its music ports with such perforations.

3. In a device of the character set forth, a traveling music-sheet, a freely suspended swinging tracker-bar movable in both directions transversely of said sheet and having a single alinement port, means actuated by the lateral deviations of the music sheet to vary the exposed portion of such alinement port 20 for moving said tracker-bar in either direction, and means for adjusting the location of such port relatively to said tracker-bar and sheet.

4. In a device of the character set forth, a music-sheet, a freely suspended swinging tracker-bar movable in both directions transversely of said sheet, a slide in said bar having a port therein, and means for adjusting said slide.

35 5. In a device of the character set forth, a music-sheet, a freely suspended swinging tracker-bar movable in both directions transversely of said sheet, and having a single alinement port, and means actuated by the 40 position of the margin of said sheet relatively to said port for automatically maintaining alinement of the music ports of said bar with the perforations in said sheet.

6. In a device of the character set forth, a music-sheet, a freely suspended swinging tracker-bar movable in both directions transversely of said sheet and having a port therein, a pneumatic actuated by the lateral deviations of said sheet to expose or cover a 45 greater portion of such alinement port, and connecting means from said pneumatic to said bar for moving the latter.

7. In a device of the character set forth, a traveling music-sheet, a tracker-bar suspended by links and arranged to be swung in both directions transversely of said sheet, and having a single alinement port, and means actuated by the position of the margin of said sheet relatively to such port, for 55 automatically swinging said bar and maintaining alinement of the music ports thereof with the perforations in said sheet.

8. In a device of the character set forth, a traveling music-sheet, a freely suspended 60 swinging tracker-bar movable in both direc-

tions transversely of said sheet, a slide movable longitudinally of said bar and having a port therein, a rod mounted on said bar and adjustably connected thereto, and a pneumatic actuated by the lateral deviations 70 of said sheet to expose or cover a greater portion of such alinement port and connecting means from said pneumatic to said rod.

9. In a device of the character set forth, a traveling music-sheet, a freely suspended 75 swinging tracker-bar movable in both directions transversely of said sheet, a slide movable longitudinally of said bar, having a port and a slot therein, a rod mounted on said bar, a screw on the latter, a nut on said 80 screw, received in and matching to such slot, and a pneumatic actuated by the lateral deviations of said sheet to expose or cover a greater portion of such alinement port, and connecting means from said pneumatic to 85 said rod.

10. In a device of the character set forth, a traveling music-sheet, a tracker-bar movable in both directions transversely of said sheet, a single alinement port in said bar 90 adapted to be controlled by said sheet, a pneumatic comprising a base having two cavities therein, a diaphragm for each cavity, one of greater area than the other, an air tube leading from such port to the cavity having the 95 larger diaphragm, an air-exhaust tube leading from the cavity having the smaller diaphragm, a bleed passage connecting such cavities, and means actuated by the movements of said diaphragms for moving said 100 tracker-bar.

11. In a device of the character set forth, a traveling music-sheet, a tracker-bar movable in both directions transversely of said sheet, a single alinement port in said bar 105 adapted to be controlled by said sheet, a pneumatic comprising a base having two cavities therein, a diaphragm for each cavity, one of greater area than the other, an air tube leading from such port to the cavity having the larger diaphragm, an air-exhaust tube leading from the cavity having the smaller diaphragm, a bleed passage connecting such cavities, means for adjustably controlling such passage, and means actuated 110 by the movements of said diaphragms for moving said tracker-bar.

12. In a device of the character set forth, a traveling music-sheet, a tracker-bar movable in both directions transversely of said sheet, a single alinement port in said bar adapted to be controlled by said sheet, a pneumatic comprising a base having two 120 cavities therein, a diaphragm for each cavity, one of greater area than the other, an air tube leading from such port to the cavity having the larger diaphragm, an air-exhaust tube leading from the cavity having the smaller diaphragm, a bleed passage connecting such cavities, a rock-shaft between said 125 130

cavities, a beam on said shaft connected to said diaphragms, an arm on said shaft, and a connection from said arm to said tracker-bar for moving the latter by the 5 movements of said diaphragms.

13. In a device of the character set forth, a traveling music-sheet, a tracker-bar movable in both directions transversely of said sheet, a slide movable longitudinally of said 10 bar, having a port and a slot therein, a rod mounted on said bar, a screw on the latter, a nut on said screw, received in and matching to such slot, a pneumatic comprising a base having two cavities therein, a dia- 15 phragm for each cavity, one of greater area than the other, an air tube leading from such port to the cavity having the larger diaphragm, an air-exhaust tube leading from the cavity having the smaller dia- 20 phragm, a bleed passage connecting such cavities, and means actuated by the movements of said diaphragms for moving said tracker-bar.

14. In a device of the character set forth, 25 a traveling music-sheet having music perforations, a tracker-bar movable transversely of said music-sheet and having music ports, a rod slidably mounted on said bar, means for adjusting the position of said bar longitudinally on said rod, and means for moving said rod and bar together longitudinally, whereby the position of said music ports may be shifted transversely of said sheet relatively to such perforations.

30 15. In a device of the character set forth, a traveling music-sheet having music perforations, a tracker-bar movable in both directions transversely of said sheet and having music ports, a slide movable longitudinally of said bar, having an alinement port and a slot, a rod slidably mounted on said bar, a screw on said rod, a nut on said screw received in and matching to such slot, means for adjusting the position of said bar longitudinally on said rod, and means actuated by the lateral deviations of said sheet to expose or cover a greater portion of such alinement port, for moving said rod and bar together longitudinally, whereby the position of said music ports may be shifted transversely of said sheet relatively to such perforations.

35 16. In a device of the character set forth, a traveling music-sheet having music perforations, a tracker-bar movable transversely of said music-sheet and having music ports, a rod slidably mounted on said bar, rack-teeth on said rod, a pinion on said bar in mesh with said teeth, means for turning 40 said pinion, notches on said rod, a dog on said bar adapted to engage such notches, and means for moving said rod and bar together longitudinally, whereby the position of such music ports may be shifted trans-

versely of said sheet relatively to such perforations. 65

17. In a device of the character set forth, a traveling music-sheet having music perforations, a tracker-bar movable in both directions transversely of said sheet and having music ports, a slide movable longitudinally of said bar, having an alinement port and a slot, a rod slidably mounted on said bar, a screw on said rod, a nut on said screw, received in and matching to said slot, 70 rack-teeth on said rod, a pinion on said bar in mesh with said teeth, and means for turning said pinion, notches on said rod, a dog on said bar adapted to engage such notches, a pneumatic actuated by the vibration of exposure of the area of such alinement port by said sheet, and connections from said pneumatic to said rod, whereby said rod and bar are movable together longitudinally and said music ports may be shifted transversely 75 of said sheet relatively to such perforations. 80

18. A tracker-bar mounted to move transversely of a music-sheet, means for moving said bar automatically to maintain alinement of its music ports with the music perforations of said sheet, means carried by the tracker-bar for shifting said bar to vary the key in which the music is played, and means for holding said bar in such shifted position. 90

19. A tracker-bar mounted to move transversely of a music-sheet and having an alinement port, means actuated by the position of said sheet relatively to such alinement port for automatically maintaining alinement of the music ports of said bar with the music perforations of said sheet, and means carried by the tracker-bar for shifting said bar and alinement port to vary the key in which the music is played and to 100 maintain the alinement. 105

20. A tracker-bar mounted to move transversely of a music-sheet, a rod for moving said bar to maintain alinement of its music ports automatically with the music perforations of said sheet, means carried by the tracker-bar for shifting said bar relatively to said rod to vary the key in which the music is played, and means for holding said bar in the shifted position. 110

21. A tracker-bar mounted to move transversely of a music-sheet, a rod for moving said bar to maintain alinement of its music ports automatically with the music perforations of said sheet, rack-teeth on said rod, a pinion on said bar in mesh with said teeth, means for turning said pinion, notches in said rod, and a dog on said bar adapted to engage such notches. 120

In testimony that I claim the invention 125 above set forth I affix my signature.

NUNEZ CLARENCE FERRIS.
